UNITED STATES PATENT OFFICE

166,581

CARPET OR SIMILAR ARTICLE

George V. Uihlein, Worcester, Mass., assignor to
M. J. Whittall Associates, Inc., Worcester, Mass.

Application January 15, 1952, Serial No. 18,064

Term of patent 3½ years

(Cl. D92—4)

To all whom it may concern:

Be it known that I, George V. Uihlein, a citizen of the United States of America, residing in Worcester, county of Worcester, and State of Massachusetts, have invented a new, original, and ornamental Design for a Carpet or Similar Article, of which the following is a specification, reference being had to the accompanying drawing, forming part thereof, wherein,

The figure on the drawing is a plan view of a carpet showing my new design.

The design unit is outlined by dotted lines and is repeated as indicated.

I claim:

The ornamental design for a carpet or similar article, substantially as shown and described.

GEORGE V. UIHLEIN.
